UNITED STATES PATENT OFFICE.

HOMER H. ARNETT, OF OSGOOD, OHIO.

LAND-ROLLER.

1,131,654.

Specification of Letters Patent. Patented Mar. 16, 1915.

Application filed September 1, 1914. Serial No. 859,644.

To all whom it may concern:

Be it known that I, HOMER H. ARNETT, a citizen of the United States, residing at Osgood, in the county of Darke and State of Ohio, have invented certain new and useful Improvements in Land-Rollers; and I do hereby declare the following to be a full, clear, and exact description of the invention, such as will enable others skilled in the art 10 to which it appertains to make and use the same.

This invention relates to rollers, of both land rolling and clod crushing types.

An object of the invention is the provision of a roller of hollow formation and having means whereby a suitable filling may be placed therein to increase its weight.

Another object is to provide a roller composed of inner and outer spaced drums, and 20 a reinforced cement filling between the drums for adding weight and giving rigidity to the device.

Another object is to provide a land roller or clod crusher of simple and durable construction, and one which may be manufactured at a comparatively low price.

A further object is to reinforce either the outer or the inner surface of the cement body or drum and also the ends thereof with 30 a covering of sheet metal if deemed necessary, or said covering may be wholly or partly omitted if desired.

In the accompanying drawing, Figure 1 represents a perspective view of the land 35 roller. Fig. 2 represents a longitudinal sectional view through one of the roller members. Fig. 3 represents a vertical sectional view therethrough, and Fig. 4 represents a fragmentary sectional view through a modified 40 form of outer drum.

Referring to the drawing, the numeral 5 indicates the frame of the roller having depending brackets 6, carrying bearing blocks 7 within which is journaled a shaft 8. A 45 draft pole 9 is attached to the frame 5 and carries a suitable seat 10.

A pair of rollers 11 is rotatably mounted over the shaft 8 and upon opposite sides of the intermediate brackets 6. Each roller is 50 composed of an outer cylindrical drum 12 and an inner cylindrical drum 13 of considerably less size than the first drum, thereby leaving a space between these parts. Each of the drums 12 and 13 is provided 55 at opposite ends with a concentric opening through which is positioned a sleeve or hub

14. Portions of the ends of the outer drums 12 are bulged inwardly at 15 adjacent the opening therein for receiving the sleeve 14.

Boxings 16 are positioned in the ends of the sleeve 14 and are provided with flanges 17 engaging the end walls of the outer drum 12. A bolt 18 or other securing device is positioned through the sleeve 14 and boxing 16 for securing these parts rigidly together. 60

The space between the outer and inner drums 12 and 13, respectively, is filled with a plastic composition such as cement for increasing the weight of the rollers at a minimum cost. The inner and outer drums are also provided with registering openings 19, the space between which is left open whereby a suitable filling of cement or gravel may be placed within the drum to increase the 75 weight thereof when desired. 70

Reinforcing plates 20 are embedded in the cement between the ends of the drums 12 and 13 and are adapted to receive the ends of the sleeve 14 to brace the latter, as can 80 readily be seen from Figs. 2 and 3 of the drawings, said plates approximately extending the diameter of the inner drum for this purpose.

U-shaped collars 21 are removably positioned over the shaft 8 between the brackets 6, and are secured thereover by a cotter pin 22 or similar device. The collars 21 are adapted to be positioned between the outer ends of the rollers 11 and the outer bearing blocks 7 when ordinary rolling or pulverizing of land is done. When it is desired to separate the rollers to straddle a row, the collars are placed between the adjacent ends of the rollers 11 and the intermediate 95 bracket 6. 85

Referring to the modification shown in Fig. 4, 25 indicates the inner drum which is similar in construction to the inner drum 13 described in the foregoing. The numeral 100 26, however, indicates an outer drum having peripheral corrugations which form is specially adapted for crushing clods. I desire it to be distinctly understood, however, that I reserve the right to make the body of my 105 improved roller with or without the outer cover of sheet metal, as said outer cover may be wholly omitted if desired and the cement surface left for direct contact with the soil. I may in some instances leave off the metal 110 covering from the face of my roller or from the ends thereof as I may deem most desir-

able in practice. I reserve the right, therefore, to employ the sheet metal covering upon the entire surface of the roller, or it may be omitted from the ends thereof and used upon the corrugated or smooth face, or it may be omitted from the corrugated or smooth face and used upon the ends, all of which is obvious and which I desire to cover and protect in this application, and I therefore deem it unnecessary to illustrate in the drawings the omission of said metallic reinforcement.

Believing that the advantages, construction and operation of my invention have thus been made clearly apparent further description is deemed unnecessary.

What I claim is:—

1. A roller comprising a shaft, a sleeve surrounding said shaft, boxings secured in the ends of said sleeve, an inner cylindrical drum surrounding said sleeve, an outer cylindrical drum surrounding said inner drum

and in spaced relation thereto, a plastic filling between the inner and outer drums, and reinforcing elements embedded in said plastic filling and engaging said sleeve.

2. A land roller comprising a frame, a shaft carried thereby, a sleeve surrounding said shaft, boxings disposed in the ends of said sleeve, an inner drum surrounding said sleeve, an outer drum surrounding said inner drum and disposed in spaced relation thereto, securing means extending through said sleeve and boxings, the ends of said outer drum being bulged inwardly to accommodate said securing means, and a plastic filling between said inner and outer drums.

In testimony whereof I have signed my name to this specification in the presence of two subscribing witnesses.

HOMER H. ARNETT.
